UNITED STATES PATENT OFFICE.

GEORGE T. TOWNSEND, OF WARREN, OHIO.

TABLE.

SPECIFICATION forming part of Letters Patent No. 267,811, dated November 21, 1882.

Application filed April 15, 1881. (Model.)

To all whom it may concern:

Be it known that I, GEORGE T. TOWNSEND, of Warren, in the county of Trumbull and State of Ohio, have invented certain new and useful 5 Improvements in Tables; and I do hereby declare that the following is a full, clear, and exact description of the invention, which will enable others skilled in the art to which it app pertains to make and use the same, reference 10 being had to the accompanying drawings, which form a part of this specification.

Figure 1 is a bottom plan of my improved table. Fig. 2 is a horizontal sectional view taken through the legs and leg-frame. Fig. 3 15 is a detail view of the leaf-support.

Corresponding parts in the several figures are denoted by like letters of reference.

This invention relates to that class of tables which are provided with folding leaves; and it 20 consists in an improved automatic leaf-support, the construction of which will be hereinafter more fully described, and particularly pointed out in the claim.

In the drawings hereto annexed, A represents 25 the table-top, under which the leg-frame B is secured in the usual manner.

C C are the folding leaves, which are hinged to the sides of the table-top, under which latter the horizontal arms or leaf-supports D D are 30 pivoted in the usual manner, slots being provided for their accommodation in the sides of the leg-frame.

E E are coiled springs, having straight ends or arms F crossing each other, and provided 35 with eyes G, enabling them to be attached respectively to the rear ends or arms of the levers or leaf-supports D, and to studs or screws H under the table, which said studs may be provided with washers I to retain the springs 40 securely in position. By the said springs the front ends of the levers or leaf-supports are automatically forced in a forward direction under the folding leaves, which thus, when raised, are retained in a horizontal position.

45 It will be observed that when the leaves are raised the supports are forced forward automatically by the springs E. In order to lower

the leaves the supports must be first pressed back by the hand under the table-top, where they are retained when the leaves are lowered 50 by the weight and pressure of the latter.

The four sides or rails J composing the leg-frame do not quite meet at the corners, and they are dovetailed at the ends, as shown at K, so as to enter corresponding dovetailed 55 grooves, L, in the sides of the legs. The latter, when adjusted and secured in this manner, are quite as rigid as when permanently secured. The leg-frame is braced and strengthened, and the legs may be readily detached 60 and packed separately for shipment, thus enabling the table to be packed in much smaller space and with less danger of breakage than when of the ordinary construction.

The advantages of my invention will be 65 readily understood from the foregoing description, taken in connection with the drawings hereto annexed. It is simple, inexpensive, and quite as durable as tables of the ordinary construction.

I am aware that a rubber band for connecting the rear end of a pivoted leaf-support to a table, whereby said support is made self-acting, is old, and such I do not wish to be understood as claiming broadly as of my invention. 75

Having thus described my invention, I claim and desire to secure by Letters Patent of the United States—

In a table, the combination, with the folding leaf C and centrally-pivoted horizontal leaf-support D, of the coiled spring E, having straight arms F crossing each other and provided with eyes or loops G, attached respectively to studs under the table and the rear end of said leaf-support, as and for the purpose 85 herein shown and described.

In testimony that I claim the foregoing as my own I have hereto affixed my signature in presence of two witnesses.

GEORGE T. TOWNSEND.
